US00D766910S

(12) **United States Design Patent** (10) **Patent No.:** **US D766,910 S**
Packulak (45) **Date of Patent:** **** Sep. 20, 2016**

- (54) **SET OF TRIGONOMETRY CALCULATOR KEYS**
- (71) Applicant: **Albert E. Packulak**, Saskatoon (CA)
- (72) Inventor: **Albert E. Packulak**, Saskatoon (CA)
- (**) Term: **14 Years**
- (21) Appl. No.: **29/508,793**
- (22) Filed: **Nov. 11, 2014**
- (51) LOC (10) Cl. **14-02**
- (52) U.S. Cl. .... **USPC D14/456; D18/12**
- (58) **Field of Classification Search**
 USPC D14/399, 320, 331, 333, 338, 346, 387, D14/388-390, 455, 456, 150, 218, 247; D18/6, 7, 8, 12, 12.1, 12.2, 24, 29; D21/324-333, 517, 512

Primary Examiner — Susan Bennett Hattan*Assistant Examiner* — Marie Fast Horse(74) *Attorney, Agent, or Firm* — Robert C. Montgomery; Montgomery Patent & Design(57) **CLAIM**

The ornamental design for set of trigonometry calculator keys, as shown and described.

DESCRIPTION

FIG. 1 is a perspective front view of the set of trigonometry calculator keys, showing my new design;

FIG. 2 is a front side view thereof;

FIG. 3 is a rear side view thereof;

FIG. 4 is a left side view thereof;

FIG. 5 is a right side view thereof; and,

FIG. 6 is a top view thereof.

The broken lines in the drawings depict the bounds of the claim, which extends to the boundary but does not include the boundary.

1 Claim, 6 Drawing Sheets(56)
